UNITED STATES PATENT OFFICE.

CHARLES LA DOW, OF ALBANY, NEW YORK.

HARROW.

SPECIFICATION forming part of Letters Patent No. 233,777, dated October 26, 1880.

Application filed July 13, 1880. (No model.)

To all whom it may concern:

Be it known that I, CHARLES LA DOW, a citizen of the United States, residing at Albany, New York, have invented new and useful Improvements in Harrows, of which the following is a specification.

This invention relates to that class of harrows having spring-teeth which are adjustable for the purpose of regulating their depth of penetration and degree of vibration on the soil, its objects being to vary the angle of the working-faces of the teeth with reference to the line of draft and to facilitate the drawing of the harrow from place to place when not in use.

15 In the accompanying drawings, Figure 1 is a plan view of a harrow constructed according to my invention. Fig. 2 is a section on line $x-x$ of Fig. 1. Figs. 3, 4, 5, 6, 7, 8, 9, and 10 are detail views of various parts of the harrow.

20 The letters A B designate, respectively, the two sections of a harrow-frame, each being composed of two beams, A' and B', diverging rearwardly, and connected by an oblique brace, a, adjustable by holes, as shown in the drawings. The two sections are connected together by eyebolts c, in order that the frame may have proper flexibility to work efficiently upon uneven ground.

25 The letter C designates the tooth-bars, mounted in the frame-sections with their outer ends inclined rearwardly, and upon these bars are secured the spring harrow-teeth D. These teeth are formed on a volute curve and preferably made of spring-steel—say about four feet in length, two inches in width, and one-fourth of an inch in thickness—with points triangular, or similar to those of ordinary cultivator-teeth, formed at their outer ends. Each tooth is fastened to its bar by having its inner end 30 placed against a flat seat formed on the under side of said bar C, as shown clearly in Fig. 9, and a bolt, d, passed through the tooth and bar. Normally the tooth touches the opposite edges only of the seat, but when strained toward the bar by the bolt it will be drawn snugly against the whole face of the seat, and its tension will prevent it from wearing loose. Each tooth is re-enforced by a stirrup, d', secured to the top of the tooth-bar by means of the tooth-bolt and its nut, and embracing the curved

inner portion of the tooth, as illustrated in Figs. 5, 9, and 10.

Each of the tooth-bars C is provided at its inner end with a bracket, e, secured to the bar by means of a socket, e', and through a hole in the cross-bar of this bracket passes the rearwardly-inclined portion f' of a bolt, f, which passes transversely through the bar B', as in Fig. 7. The bolt is of a considerably less diameter than the hole in the bracket, in order that the bar may be swung laterally, and on the screw-threaded end of the bolt, within the bracket, is fitted a nut larger than the hole, to secure the bracket and bolt together. This construction admits of the rocking of the tooth-bars back or forward at will.

Between the bracket and the bar B' is arranged a wedge-shaped elastic seat, g, which prevents bumping of the bracket against the bar, and also permits the angle which the bracket forms with the beam to be varied.

Each of the bars C is connected to the outer beam, A', by means of an adjustable bearing, h, Figs. 4 and 5, the latter being an under-side view. This bearing is provided with the ears h', having segmental slots h² formed therein, so that their position on the beam can be readily changed to permit the rearward inclination of the tooth-bars to be changed.

If the ground be well broken and soft, the tooth-bars should be arranged to present the faces of the teeth at nearly right angles to the draft; but if the ground be covered with large hard clods or stones, the tooth-bars should be inclined rearwardly sufficiently to present the faces of the teeth at such angles to the line of draft as will enable them to throw outwardly the stones, refractory clods, or other obstructions with which they may come in contact.

Each of the tooth-bars C is provided with a radially-projecting arm, E, secured to said bar by a shackle, l, to the upper half, l', of which the arm is directly attached, and preferably formed in one piece therewith, the two halves l and l' embracing the bar and secured together by bolts. The interior curved faces of the shackle are corrugated to fit upon a similarly-corrugated portion of the bar, as shown in Figs. 2 and 3, in order to give the said shackle a firm hold upon the bar.

The upper ends of the arms E are connected by a bar, F, which terminates at its rear end in a rigidly-attached toothed segmental plate, G, through which passes the pivot connecting it and the bar to the rear arm, E. The rear arm, E, is prolonged to form a lever, H, carrying a spring-bolt, H', connected by a rod or chain with a handle, H², at the top of the lever. The spring-bolt H' engages the teeth 5 of the segment G, and holds the lever thereto. By means of the lever H, and through the segmental plate, bar F, and arms E, the tooth-bars may be simultaneously turned to vary the penetration of the teeth, as 10 indicated in dotted lines. By this arrangement it will be seen I dispense with any fixed cross-bar for carrying the locking devices, and thus cheapen and simplify the construction of the implement. By this arrangement the 15 teeth are also rendered more or less vibratory and yielding, according to the work to be done. When working among stones or stumps they should be set so that they will yield more than when on smooth land. The bars may be turned 20 not only to vary the penetration of the teeth, but may be given such a movement as to bring the teeth with their convex main portions under the frame, and may be thus locked, in order to serve as runners upon which the implement 25 may be hauled from place to place, thus avoiding the labor of turning the frame upside down, as heretofore. From a point near the top of each of the arms E there projects laterally a stud, i, which fits through a 30 hole in the bar F, and said stud is bored for the passage of the bolt i', the head of which secures the bar F upon the stud, and thus the bolt is relieved of lateral strain.

The rear tooth-bar, C, of the frame-section 40 A, it will be observed, has but three teeth, the same as the others, and if the rear bar of section B had also only three teeth there would be left a considerable space at the center of the harrow where the ground would not be 45 properly worked; but to avoid this I provide the rear bar of the section B with four teeth, and to make room for the inner tooth I shorten the beam B' of the section, so as to allow the inner end of the tooth-bar to extend past its 50 end. Rearwardly from the inner surface of this shortened beam extends a plate, b, provided with a hole to receive a journal-pin projecting from the tooth-bar. The inner tooth of this bar is at about equal distances from 55 those on each side of it, and fills the gap which would be left if the bars had a uniform number of teeth.

The harrow, as now described, I provide with a draft-bar or permanent double-tree, T, having a length about equal to the width of 60 the front of the frame. The ends of this bar are connected to the opposite front corners of the frame by means of chains t, and from its middle a link, t', leads to the inner corner of one of the frame-sections—in this instance, 65 the section B, but it is not material which. This draft-bar being thus connected to the harrow at three points equal distances apart, and the outer two connections being at the corners of the frame, the draft will be applied 70 equally at all times, its tendency being to prevent lateral vibration of the harrow; but even during such vibrations as may be caused by uneven ground the draft will be equally distributed between the near and off horses. 75

Having now fully described my invention, I claim—

1. The combination, with the flexibly-connected harrow-frame sections, of the tooth-bars having their outer portions mounted in 80 adjustable bearings supported by the outer beams and their inner ends flexibly jointed to the inner beams, substantially as and for the purpose set forth.

2. The combination of the tooth-bars C, 85 having formed therein flat seats for the teeth, of the curved teeth having their curved elastic inner ends arranged to bear normally on opposite edges of said seats, and the bolts passing through said bars at about the centers 90 of the seats and through the curved inner ends of the teeth, substantially as and for the purpose set forth.

3. The combination, with the tooth-bars C, 95 having the flat spring-seats and curved teeth D secured thereto, of the stirrups d', attached to the bars embracing the teeth, and arranged to brace said teeth against outward strain, substantially as and for the purpose set forth.

4. The combination, with a harrow-frame, of 100 rotary tooth-bars provided with curved teeth capable of adjustment simultaneously to form runners upon which the harrow may be hauled from place to place, substantially as set forth.

In testimony whereof I have hereunto set 105 my hand in the presence of two subscribing witnesses.

CHARLES LA DOW.
